UNITED STATES PATENT OFFICE.

DAVID E. ROWLAND, OF CANTON, OHIO.

WRENCH.

No. 838,214.

Specification of Letters Patent.

Patented Dec. 11, 1906.

Application filed August 21, 1906. Serial No. 331,435.

To all whom it may concern:

Be it known that I, DAVID E. ROWLAND, a citizen of the United States, residing at Canton, in the county of Stark and State of Ohio, have invented certain new and useful Improvements in Wrenches; and I do hereby declare the following to be a full, clear, and exact description of the invention, such as will enable others skilled in the art to which it appertains to make and use the same, reference being had to the accompanying drawings, and to the numerals of reference marked thereon, which form a part of this specification.

My invention relates to that class of wrenches in which the movable jaw is operated or adjusted by the rotation of the handle.

The object of the invention is to provide a wrench that can be easily adjusted to fit different-sized objects upon which the wrench is to be applied, which advantages will appear in the construction and the combination of parts, as hereinafter more particularly described, and pointed out in the claims, reference being had to the accompanying drawings, forming a part.

Figure 1 is a side elevation. Fig. 2 is a longitudinal section showing the different parts of the wrench properly arranged. Fig. 3 is a transverse section on line 3 3, Fig. 2. Fig. 4 is a transverse section on line 4 4, Fig. 2. Fig. 5 is a view showing a portion of the shank and illustrating the internal screw-threaded end thereof. Fig. 6 is a detached view of the non-rotatable collar. Fig. 7 is a view showing a portion of the screw-threaded stem and illustrating the shank-collar located thereon. Fig. 8 is a detached perspective view of the handle-ferrule.

Similar numerals of reference indicate corresponding parts in all the figures of the drawings.

In the accompanying drawings, 1 represents the shank, which is formed hollow throughout its entire length and is provided with the integral jaw 2, which is of ordinary construction. The shank is also provided with the pivoted pipe-grip jaw 3, which pipe-grip jaw is of ordinary construction and has no particular reference to the present invention. Within the hollow shank 1 is normally located the stem 4, which stem is pro-

vided with the jaw 5 and may be provided with the notched or pipe-grip jaw 6 and 55 should be so provided, providing it is desirable to construct a combined nut and pipe wrench. The stem 4 is formed hollow throughout its entire length, and a portion of said shank is provided with internal screw- 60 threads, which internal screw-threads are for the purpose of receiving the screw-threads upon the handle-stem 7, said screw-threads being for the purpose of providing adjustment as between the jaw on the shank 1 and 65 the jaws upon the stem 4.

The shank 1 is provided with the shoulders 8, which shoulders are for the purpose of forming seats for the non-rotatable collar or disk 9, which disk is provided upon one of its 70 sides or faces with the plain-faced edges 10, which plain-faced edges are seated adjacent the plain-faced edges 11, formed upon the shank 1, as best illustrated in Fig. 5, said plain-faced edges 10 and 11 being for the purpose of 75 holding the disk 9 against rotation during the time the wrench-jaws are adjusted to and from each other or during the time the handle-stem is rotated. The handle-stem 7 is provided with the flange 12, which flange is located between 80 the collar or disk 9 and the shank-collar 13. Said collar 13 is secured to the shank 1 and held in fixed relationship therewith by means of screw-threads or their equivalents. The handle-stem 7 is provided with the tapered handle-attaching portion, upon which 85 portion is mounted the handle 14, which handle is held by means of the screw-threaded nut 15, located upon the screw-threaded part of the tapered handle portion. The 90 handle-stem 7 is provided with the lugs 16, which lugs are seated in the notches 17, formed in the web 18 of the ferrule 19. The ferrule 19 is located upon the handle 14, as 95 illustrated in Figs. 1 and 2, and for the purpose of causing the ferrule to rotate with the rotation of the handle 14 and in turn causing the handle-stem 7 to rotate with the handle the webs or flanges 20 are formed upon the web 18, which flanges are seated in the handle, and the lugs 16 seated in the notches 17. 100

For the purpose of providing a means for rotating the shank-collar 13 it is provided with the angled flange portion 21, upon which a wrench can be applied.

It will be understood that when the handle

14 is rotated it will also rotate the handle-stem 7, which rotation will impart a longitudinal movement to the stem 4. By locating the flange 12 between the disk 9 and the collar 13 and spacing said parts from each other a distance equal to the thickness of the flange 12, or substantially so, there can be no end movement of the handle-stem 7 independent of the non-adjustable parts of the wrench, thereby holding the handle-stem during the time of its rotation. The non-screw-threaded portion of the stem 4 is formed somewhat larger in diameter than the extreme diameter of the handle-stem 7 and is so formed for the purpose of providing a space between the outer edges of the screw-threads, by which arrangement there is less liability of any binding as between the stem 4 and the handle-stem 7. It is well understood that in use heavy strain is frequently brought upon the wrench, which in some instances may have a tendency to slightly spring the handle-stem, which would cause the handle-stem to bind to a greater or less extent if the screw-threads were extended throughout the entire length of the stem 4. To facilitate in properly molding the stem 4, it is formed hollow throughout its entire length and must be so molded to carry out the advantages derived from the open ends of the shank. It will be understood that by providing the collar 9 and locating the same as described the flange 12 will be seated against the face of said collar, thereby providing a perfect seat for said flange to rotate against. By providing the collar 9 and detachably connecting the same to the shank 1 I am enabled to easily remove said collar for any purpose, such as cleaning the inner surface of the shank 1 or for any other purpose.

Having fully described my invention, what I claim as new, and desire to secure by Letters Patent, is—

1. In a wrench of the class described, the combination of a hollow shank provided with a fixed jaw, a hollow stem provided with a jaw, said hollow stem provided with internal screw-threads, a screw-threaded handle-stem, and a handle mounted thereon, the shank provided with a flange, collars spaced from each other and carried by the hollow shank, lugs formed upon the handle-stem, a handle-ferrule provided with a web, said web provided with notches and the lugs formed upon the handle-stem adapted to be seated in the notches of the ferrule-web, substantially as and for the purpose specified.

2. In a wrench of the class described, a shank, and a stem located therein, said shank and stem provided with jaws, means for imparting longitudinal movement to the stem located in the shank, a handle-stem provided with a flange, collars located upon the opposite sides of the flange and a handle-stem and

means for imparting rotary motion to the handle-stem, substantially as and for the purpose specified.

3. In a wrench of the class described, the combination of a shank and a stem each provided with a jaw, a handle-stem normally located in the stem provided with a jaw, a handle mounted upon the handle-stem, and a ferrule provided with a notched web, lugs formed upon the handle-stem and adapted to be seated in the notched web, a flange located upon the handle-stem, collars carried by the shank, and spaced from each other and the flange of the handle-stem located between the collars, substantially as and for the purpose specified.

4. In a wrench of the class described the combination of an open-ended hollow shank and a hollow stem each provided with a jaw, a screw-threaded handle-stem partially located in said hollow stem, a portion of said hollow stem provided with screw-threads, adapted to receive the screw-threads of the handle-stem, and a portion of said hollow stem formed non-screw-threaded, said non-screw-threaded portion having a diameter greater than the diameter of the handle-stem located within said hollow stem, a handle located upon the handle-stem, means for rotating the handle-stem by the rotation of the handle and means for holding said handle-stem against longitudinal movement with reference to the shank when rotated, substantially as and for the purpose specified.

5. In a wrench of the class described, the combination of a shank, a stem slidably mounted therein, a handle-stem, and a handle mounted thereon, and rotatable therewith, said handle-stem provided with a flange, collars carried by the shank, and the handle-stem held against the longitudinal movement by the collars, substantially as and for the purpose specified.

6. In a wrench of the class described the combination of a shank, and a stem slidably mounted therein, said stem provided with a detachable collar and a fixed collar, said collars spaced from each other, a handle-stem provided with screw-threads and the slidable stem provided with screw-threads corresponding with the screw-threads upon the handle-stem and a flange located between the detachable collar and fixed collar carried by the shank, substantially as and for the purpose specified.

7. In a wrench of the class described, the combination of a hollow shank and a hollow stem each provided with a jaw, the hollow stem slidably mounted in the shank and formed hollow throughout its entire length, said hollow stem provided with internal screw-threads for a portion of its length and a non-screw-threaded portion formed of a diameter greater than the diameter of the

screw-threaded portion a handle-stem located in the hollow stem and a handle mounted upon the handle-stem, and rotatable therewith and means for holding the handle-
5 stem against longitudinal movement with reference to the shank, substantially as and for the purpose specified.

In testimony that I claim the above I have hereunto subscribed my name in the presence of two witnesses.

DAVID E. ROWLAND.
